(57) **CLAIM**

The ornamental design for a display screen or portion thereof with graphical user interface, as shown and described.

DESCRIPTION

FIG. 1 is a front view of a display screen or portion thereof with graphical user interface, according to a first embodiment of the claimed design.

FIG. 2 is a rear view of the display screen or portion thereof with graphical user interface of FIG. 1.

FIG. 3 is a top view of the display screen or portion thereof with graphical user interface of FIG. 1.

FIG. 4 is a bottom view of the display screen or portion thereof with graphical user interface of FIG. 1.

FIG. 5 is a left side view of the display screen or portion thereof with graphical user interface of FIG. 1.

FIG. 6 is a right side view of the display screen or portion thereof with graphical user interface of FIG. 1; and,

FIG. 7 is a front view of a display screen or portion thereof with graphical user interface, according to a second embodiment of the claimed design.

The dash-dot-dash broken lines showing the display screen and the dash-dash broken lines in FIGS. 1-7 showing the display screen portion and graphical user interface illustrate portions of the display screen or portion thereof with graphical user interface that form no part of the claimed design. The rear view, top view, bottom view, left side view, and right side view of the display screen or portion thereof with graphical user interface of FIG. 7 is the same as shown by FIGS. 2, 3, 4, 5, and 6, respectively.
